UNITED STATES PATENT OFFICE.

ALBERT OWEN HOLTOM, OF ROCHESTER, NEW YORK, ASSIGNOR TO HERMAN EDWARD ZIMMERMAN, OF NEW YORK, N. Y.

DESIGN FOR AN AUTOMOBILE RADIATOR CASING.

Application filed January 10, 1927. Serial No. 20,324. Term of patent 7 years.

To all whom it may concern:

Be it known that I, ALBERT O. HOLTOM, a citizen of the United States, residing at Rochester, in the county of Monroe and State of New York, have invented a new, original, and ornamental Design for Automobile Radiator Casing, of which the following is a specification, reference being had to the accompanying drawing, forming part thereof.

Figure 1 is a top plan view of an automobile radiator casing showing my new design;
Figure 2 is a front elevation of the same;
Figure 3 is a side elevation of the same.

I claim:

The ornamental design for an automobile radiator casing as shown.

ALBERT OWEN HOLTOM.
